UNITED STATES PATENT OFFICE.

HARRY H. ABBOTT AND NELSON L. DEAN, OF COLDWATER, MICHIGAN.

EXPLOSIVE-ENGINE.

1,100,279.

Specification of Letters Patent. Patented June 16, 1914.

Application filed March 29, 1911. Serial No. 617,597.

To all whom it may concern:

Be it known that we, HARRY H. ABBOTT and NELSON L. DEAN, citizens of the United States of America, residing at Coldwater, in the county of Branch and State of Michigan, have invented certain new and useful Improvements in Explosive-Engines, of which the following is a specification, reference being had therein to the accompanying drawings.

In the usual arrangement of a two-cycle internal combustion engine the velocity with which the charge is injected into the compression end of the cylinder does not vary as the speed increases or decreases, but is necessarily constant.

This invention relates to a two-cycle internal combustion engine wherein provision is made to vary the time of the intake of the charge in proportion to the speed of the engine and wherein also the amount of the charge can be varied at will.

The invention also includes certain features resulting in the disposition of the parts whereby the bearings and like wearing members are made few in number and whereby a multi-cylinder engine is obtained which is compact and which is simple and effective.

The invention consists in the matters hereinafter set forth and more particularly pointed out in the appended claims.

In the drawings, Figure 1 is a view in sectional elevation through one pair of cylinders and the adjacent parts of a motor embodying features of the invention; Fig. 2 is a view in section taken through the cylinders and a supply cylinder on or about line $x-x$ of Fig. 1 and with the parts projected in the same plane; Fig. 3 is a view in detail of the supply cylinder operating shaft; Fig. 4 is a view in longitudinal section through a supply cylinder taken on line $y-y$ of Fig. 1; Fig. 5 is a view similar to Fig. 2, of a modified form of the device; and Fig. 6 is a view in longitudinal section of the supply cylinder of the modified form.

As herein indicated the motor is shown of a four-cylinder type in which cylinders are disposed in pairs at 90 degrees to each other. A crank shaft 1 has a pair of oppositely disposed crank pins 2, in the same plane and consequently 180 degrees apart or diametrically opposite. A pair of opposite cylinders 3 and 4 are disposed at 90 degrees to each other. Each have their pistons 5 and

6 coupled by connecting rods 7 and 8 to one crank pin 2 while a pair of similarly disposed cylinders 9 and 10 have their pistons respectively coupled in a similar manner to the second crank pin. As a consequence the cylinders are operated in the order 3, 4, 9 and 10. Each cylinder has an intake port 11 and an outlet or exhaust port 12.

A supply cylinder 13 is disposed between the other cylinders in a line parallel to the crank shaft 1. A pair of oppositely disposed outlet ports 14 and 15 at one end of the cylinder 13 are in communication with the intake ports 11 of the cylinders 3 and 4 while a second pair of outlet ports 16 and 17 at the other end of the supply cylinder discharge into the corresponding intake ports of the cylinders 9 and 10. As shown in Fig. 2 the cross sectional area of the supply cylinder is double or little more than double that of each of the main cylinders. A valve casing 19, provided with a fuel supply pipe 20 leading from a carburetor or the like, is mounted on the supply cylinder 13 and is in communication with each end thereof through intake valves 21 and 22, preferably of the automatic outwardly closing type. Outlets 23 and 24 through which the charge passing through these valves ultimately reach this cylinder are connected by a bypass indicated at 26 and controlled by a manually operable valve or closure 25.

A piston 27 playing in the cylinder 13 is driven from the main shaft 1 through any suitable mechanism to have the same number of strokes per revolution of the crank shaft as do the main cylinder pistons with a throw equal to that of the main cylinder pistons in case the cross-sectional area of the supply cylinder is double that of the other cylinders. As herein indicated as a preferred form of such mechanism, a pair of equal miter gears 28 and 29 connect the engine crank shaft 1 with a transverse shaft 30 carrying a wrist plate 31 and wrist pin 32. The latter revolves concentrically within an internal gear 33 mounted on an extension 34 of the engine casing. A spur pinion 35 is journaled on the pin 32 in mesh with the internal gear 33. The pitch diameter of the pinion 35 is one-half the pitch diameter of the internal gear 33, and a pin 36 is mounted on an arm 37 carried on the face of the pinion 35 on the pitch line thereof. The pin is journaled in a bearing at the end of a piston rod 38 connected to the supply cylinder piston 27 so that as

the pin 32 rotates the pin 36 travels back and forth along the diametrical line indicated at Z that is an extension substantially of the axis of the supply cylinder 13. This prevents any side movement of the piston and gives the required stroke thereto.

In the operation of the form of motor just described, if the parts are in the position shown in Fig. 1, the movement of the piston 27 of the supply cylinder half-way toward the ports 14 and 15 thereof forces one-half of the contents of the supply cylinder through the inlet port 11 and into the cylinder 4, the position of the pistons in relation to the inlet ports 11 of the main cylinders 3 and 4 being so disposed as to permit this. When this one-half stroke has been completed the piston of the cylinder 4 has closed its inlet port 11 and at the same time the piston of the companion cylinder 3 commences to open its inlet port 11 so that the completion of the stroke of the supply cylinder piston 27 forces the remaining half of the supply cylinder contents into the cylinder 3. At the same time the displacement on the other side of the supply cylinder piston and consequent tendency to cause a vacuum, has drawn a full charge into the supply cylinder 13 through the carbureter valves and the inlet port 23 at that end of the supply cylinder. The reverse stroke of the supply cylinder piston for half its length forces one-half of the contents of the supply cylinder through the inlet port of the cylinder 9 which is uncovered during this time by the piston of the latter, and during the remainder of the stroke, is filling the cylinder 10 through its inlet port.

To increase the effectiveness of the intake of the cylinder the piston heads have baffles disposed as indicated at 50 directing the incoming charge against the head of the cylinder and allowing the exhaust charges to be scavenged or driven ahead and cut through the exhaust ports indicated at 12.

If it is desired to diminish the amount of carbureted air that is indrawn, the closure 25 controlling the by-pass indicated at 26 is opened to a greater or less extent thereby 50 allowing the charge displaced by the supply cylinder piston to be moved from one end of the supply cylinder to the other end without wholly entering the main.

In the modification shown in Figs. 5 and 6, a supply cylinder 39 is provided of the same capacity as the main cylinders. Its piston 40 is driven from a transverse shaft 41 turning at twice the speed of the main shaft 1 as through the medium of suitably proportioned bevel gears 42. The stem 43 of the piston may be driven by the same device as shown in Figs. 2 and 3, or may have other suitable connections such as a slotted yoke 44 engaged by a pin 45 on a wrist plate 46. The inlet valves may be arranged

as indicated at 47 and by-passes shown at 48 may connect the main cylinder inlet ports 49.

The disposition of the cylinders minimizes the number of crank shaft connections and bearings while rigidity is obtained by the arrangement of the cylinders, in which the supply cylinder acts as a strut connecting the diverging bodies of the main cylinders. 70

Obviously, changes in the details of construction may be made without departing from the spirit of the invention and we do not care to limit ourselves to any particular form or arrangement of parts. 75

What we claim is:

1. The combination in a two-cycle engine, of a main casing, a main crank shaft journaled therein, a pair of cylinders for each crank of the shaft disposed at right angles to each other, pistons in the cylinders each controlling an inlet and an outlet port of the cylinder, the pistons of each pair of cylinders being coupled with a common crank, a supply cylinder disposed between the main cylinders having an inlet valve at each end, and an outlet valve at each end in communication with the inlet ports of the adjacent pair of cylinders, a piston for the supply cylinder, and means for restricting and controlling a passage that connects the outlets of the inlet valves of the supply cylinder. 80

2. The combination in a two-cycle engine, of a main casing, a crank shaft journaled therein, pairs of divergent cylinders mounted on the casing, pistons for the cylinders, the pistons of each pair being coupled to a common crank of the shaft, a supply cylinder disposed transversely to and between the pairs of divergent cylinders and provided with an inlet valve at each end and an outlet port at each end and in communication with the inlet ports of the adjacent pair of cylinders, a piston for the supply cylinder for forcing the charge therein through the outlet ports and indrawing the charge through the inlet ports, means for operating the supply cylinder piston in timed relation to the other pistons, and a valve for restricting a passage that connects the outlets of the inlet valves of the supply cylinder. 100

3. In a two-cycle engine the combination of a main casing, pairs of divergent cylinders disposed thereon with their bases in communication with the casing, a piston 120 for each cylinder controlling an inlet and an outlet port therein, a crank shaft journaled in the casing, the cranks of which are each coupled to a pair of pistons of companion cylinders, a supply cylinder disposed transversely to and between the main cylinders substantially as an extension of the main casing, and provided with an inlet valve at each end and an outlet port at each end in communication with the ports of the adjacent 125 cylinders. 130

pair of cylinders, a piston reciprocating in the supply cylinder, means operatively coupling the supply cylinder piston to the crank shaft to operate in timed relation to the main pistons and a single controlling valve for restricting a passage of the supply cylinder that connects the outlets of the inlet valves thereof.

In testimony whereof we affix our signatures in presence of two witnesses.
